UNITED STATES PATENT OFFICE.

FRANK C. HINCKLEY, OF BRIDGEPORT, CONNECTICUT, ASSIGNOR TO AMERICAN GRAPHOPHONE COMPANY, OF BRIDGEPORT, CONNECTICUT, A CORPORATION OF WEST VIRGINIA.

MANDREL FOR SOUND RECORDING OR REPRODUCING MACHINES.

1,291,516.

Specification of Letters Patent. Patented Jan. 14, 1919.

Application filed February 20, 1917. Serial No. 149,886.

To all whom it may concern:

Be it known that I, FRANK C. HINCKLEY, a citizen of the United States of America, and a resident of Bridgeport, Connecticut, have invented a new and useful Improvement in Mandrels for Sound Recording or Reproducing Machines, which invention is fully set forth in the following specification.

10 This invention relates to sound-recording and reproducing machines, and more particularly to the sound-record tablet support and its associated elements.

It is an object of this invention to provide 15 a mandrel for a cylindrical sound-record with efficient and easily operated means for locking the record-tablet upon the mandrel.

It is a further object of this invention to provide, in combination with a mandrel for 20 cylindrical sound-records, means for ejecting the record-tablet therefrom, means for locking the tablet upon the mandrel, and a common actuating means for withdrawing the record-locking means and operating the 25 record-ejecting means.

Other objects will appear as the description of the invention proceeds.

Stated briefly, the invention comprises the combination in a sound-recording or reproducing machine with a mandrel for a cylindrical sound-record of means, preferably in the form of a latch, for locking the record-tablet upon the mandrel and a manually-operable device, movably mounted and operatively connected with the latch, for moving the latter into and out of record-engaging position. Also associated with the mandrel, by preference, is a record-ejecting means, preferably actuated by the backward rotation of the mandrel, in which event the manually-operable actuating device for withdrawing the record-locking means is so related to the record-ejecting means that said device constitutes a common actuating device 45 for both the record-ejecting means and the record-locking means.

The invention is capable of receiving a variety of mechanical expressions, one of which is shown in the accompanying drawings; but it is to be expressly understood that such drawings are for the purpose of illustration only and are not to be construed

as a definition of the limits of the invention, reference being had to the appended claims for that purpose.

55 In said drawings:

Figure 1 is an end elevation of a sound-recording or reproducing machine embodying the present invention;

Fig. 2 is a fragmentary end elevation of 60 the opposite end of said machine, with certain cover plates removed for clearness of illustration;

Fig. 3 is a longitudinal sectional view 65 through the mandrel and its associated parts, but illustrating for convenience but a pair of diametrically disposed ejecting lugs;

Fig. 4 is a perspective of the record-ejecting device, with the elements thereof in separated relationship; and 70

Fig. 5 is a vertical sectional view on the line 5-5 of Fig. 3:

Referring in detail to the drawings, wherein the same reference numerals indicate corresponding parts in the several figures, 1 designates the frame of a sound-recording or reproducing machine of any preferred construction, that illustrated on the drawings being of the type shown in my application Serial No. 156,044, filed Mar. 20, 1917. As here shown, said frame 1 is in the form of a relatively small base 2 provided with supporting posts 3 and having at opposite ends thereof standards 4 and 5. Supported by said standards is one or more 80 guides 6, such guide or guides desirably being made hollow and containing a feed-screw or feed screws 6' as illustrated in Fig. 3. Supported to travel upon said guides 6 is a recorder or reproducer frame 7 provided with a suitable sound-box 8 and sound-conduit connections 9. Also mounted upon the frame 1 is a suitable motor 10, such for example as that described and claimed in the application of Clinton E. Woods, Serial No. 149,553, filed Feb. 19, 1917. Mounted upon shaft 11 of said motor 10, as shown, is a belt wheel 12 in alinement with a belt wheel 13 mounted upon the projecting end of mandrel shaft 14. A belt 15 is passed around said belt wheels 12 and 13 and, if desired, a suitable belt-tightener, as illustrated at 16, may be employed to maintain the proper frictional engagement between the belt and said

75

80

85

90

95

100

wheels. Said belt, wheels, and the belt-tightener when employed, are desirably inclosed within a housing 17 provided, as shown, with a detachable cover plate 18. 5 The mandrel shaft 14 is also shown as provided with a pinion 19 driving a gear train 20 operatively connected with the feed-screw or screws. Said gear train is also preferably inclosed within a housing 21 provided 10 with a detachable cover plate 22. While the form of sound-recording or reproducing machine illustrated on the drawings is that specifically illustrated in my application heretofore referred to, it is to be expressly 15 understood that the invention is not restricted to use in any particular form of machine but is susceptible of use wherever a mandrel for a cylindrical sound-record is employed.

20 Referring particularly to Figs. 3, 4 and 5, mandrel shaft 14 is shown as having bearing within an elongated boss 23 projecting from one face of the standard 5, the bearings being indicated diagrammatically at 24 and 25. Mounted upon the projecting end of said mandrel shaft 14 to rotate therewith is the hub 26 of a mandrel 27 for supporting and rotating a cylindrical record-tablet 28. Said mandrel is preferably of the usual 25 tapered construction to conform with the usual tapered bore of a cylindrical record-tablet. If desired, the bearing 25 of the mandrel shaft 14 may be automatically lubricated by a suitable oiling device as shown 30 at 29, illustrated as provided with a spring-pressed depressible plug 30 in the outer end of the mandrel.

Mounted for rotation upon the outermost end of mandrel shaft 14 is a manually operable device in the form of a knob or hand-wheel 31 which may desirably be knurled to facilitate manual operation of the same. Said knob or hand-wheel 31 is also desirably mounted for longitudinal movement 45 upon the end of said mandrel shaft 14, in which event it is preferably provided for a portion of its length with an enlarged bore as shown at 32. Between the shoulder 33 formed by one end of said enlarged bore 50 and a washer 34 suitably secured on the end of the shaft 14, is positioned a spring 35 normally urging said knob or hand-wheel 31 in the direction of the mandrel. Said knob or hand-wheel 31 is furthermore provided with 55 one or more ears 36 to which is loosely pivoted, as by a pin and slot connection 37, one end of a latch 37 provided at its opposite end with an inwardly directed nose 38. Said latch 37 is pivotally mounted upon the 60 mandrel and, by preference, has longitudinal movement toward and from the end of said mandrel. As shown, said mandrel is provided with an elongated bushing 39 within which is a pin 40 extending beyond the 65 end of the mandrel and engaging within an

aperture 41 in said latch 37. The end of the pin is preferably headed over, as illustrated at 42, to prevent disengagement of said pin and said latch.

Associated with the mandrel 27, by preference, is a record-ejecting device, that illustrated being similar in certain respects to the construction described and claimed in the patent to Frank L. Capps, No. 1,119,065, dated December 1, 1914. As shown, a sleeve 70 43 is mounted for reciprocatory movement within said mandrel 27 and is provided with one or more radial lugs 44 which may move longitudinally in one or more slots 44' provided therefor in the mandrel. As a stop 75 for said lugs, said mandrel may desirably carry an end ring 45. Sleeve 43 at its opposite end is provided with an inwardly directed flange 46 adapted to coact with one or 80 more rollers 47. Mounted on boss 23 is a 85 collar 49 fixed in relation to said boss as by a set-screw 50. Said collar 49 is provided at its inner edge with one or more notches 51, there being as many notches as there are rollers. Each notch, as shown, is 90 provided with an abrupt shoulder 52 at one side and with a gradually inclined surface 53 at its opposite side.

To normally urge sleeve 43 in a direction to maintain rollers 47 in the bottoms of the 95 notches 51, one or more spring-pressed pins 54 are carried by bosses 55, projecting from the interior of the mandrel and desirably integral therewith, and engage the outer face of the inwardly directed flange 46. 100

In operation, assuming the parts to be in the relative positions shown in the drawings, rotation of the motor with its shaft 11 produces a rotation of mandrel shaft 14 through the belt wheel drive, as illustrated, with a 105 consequent rotation of the mandrel and the sound-record tablet supported thereon in the direction of the arrow 56 shown in Fig. 3. So long as the mandrel rotates in this direction, sleeve 43 is pressed to its outward position by the spring-pressed pins 54, rollers 47 taking up positions within the deepest portions of the notches 51, and rotating freely therein. The machine being stopped and the record to be withdrawn, knob 31 is 110 drawn longitudinally outward upon the end of mandrel shaft 14, carrying therewith latch 37 owing to the reciprocatory movement provided for pivot pin 40, whereby nose 38 is withdrawn from engagement with 115 the sound-record tablet. Knob 31 is thereupon rotated in the direction of arrow 57 shown in Fig. 3. Rotation of said knob causes a pivotal movement of latch 37 about the axis determined by pivot pin 40 until 120 nose 38 is withdrawn within the periphery of the end of mandrel 27, the requisite play between the ears 36 and said latch being provided by the pin and slot connection 37' therebetween. When the latch has assumed 125 130

the last-named position, further pivotal movement thereof is prevented by engagement of the pin with the end of the slot at 37', and further rotation of knob 31 in 5 the last-named direction is thereupon transmitted through pivot pin 40 to the mandrel 27, giving said mandrel a backward rotation. As the mandrel rotates backwardly, sleeve 43, rotating therewith, is forced inwardly 10 against the tension of the spring-pressed pins 54 as the rollers 47 are forced to roll up the inclined sides of notches 51. Thereby the radial lugs 44 are forced into engagement with the end of the sound-record tablet 15 and the same is loosened from the mandrel and ejected to a position where it may be readily grasped by the hand. Further rotation of the mandrel in the backward direction will bring rollers 47 into the next succeeding 20 notches, whereupon spring-pressed pins 54 will return sleeve 43 with its radial lugs 44 to their outermost position.

When a new record-tablet is positioned upon the mandrel, knob 31 is drawn outwardly and rotated in the reverse direction, thereby swinging latch 37 in the reverse direction until its inwardly directed nose 38 is in alignment with the sound-record tablet, whereupon knob 31 is released and spring 35 30 forces said knob, together with the latch, longitudinally of the mandrel until nose 38 engages the record-tablet and securely locks the same in position.

While the illustrated embodiment has 35 been described with considerable particularity, it is to be expressly understood that the invention is not to be restricted to the precise form shown, but is susceptible of receiving a variety of embodiments, some of 40 which will readily suggest themselves to those skilled in the art; furthermore, certain features thereof are capable of use without other features thereof; reference is therefore to be had, for a definition of the limits of 45 said invention, to the claims hereto appended, wherein the term "talking machine" is to be construed as of a scope to include either sound-recording or sound-reproducing machines.

50 What is claimed is:

1. The combination in a talking machine of a mandrel for a cylindrical sound-record, means for locking the record on said mandrel, and a single means for releasing the 55 record and ejecting the same.

2. The combination in a talking machine of a mandrel for a cylindrical sound-record, a latch for engaging a record on the mandrel to prevent accidental removal therefrom, 60 and a single means for withdrawing said latch and ejecting the record.

3. The combination in a talking machine of a mandrel for a cylindrical sound-record, means for locking the record on said mandrel, means for ejecting the record from said 65

mandrel, and a common operating means for said record-locking and record-ejecting means.

4. The combination in a talking machine of a mandrel for a cylindrical sound-record, 70 a latch for engaging a record on the mandrel to prevent accidental removal therefrom, means for ejecting the record from said mandrel, and a common actuating means for withdrawing said latch and operating said ejecting means.

5. The combination in a talking machine of a mandrel for a cylindrical sound-record, 80 a latch at one end of the mandrel for engaging a record thereon to prevent accidental removal therefrom, a manually rotatable device at one end of the mandrel, means operable by said device for withdrawing the latch, and means operable by said device for ejecting the record.

6. The combination in a talking machine of a mandrel for a cylindrical sound-record, 85 a latch at one end of the mandrel for engaging a record thereon to prevent accidental removal therefrom, an axially-movable and rotatable device at one end of the mandrel, means operable by said device for withdrawing the latch, and means operable by said device for ejecting the record.

7. The combination in a talking machine 95 of a mandrel for a cylindrical sound-record, a latch mounted on the mandrel and movable in a plane perpendicular to the axis thereof into and out of record-engaging position, and a single means for moving the 100 latch out of record-engaging position and subsequently ejecting the record.

8. The combination in a talking machine of a mandrel for a cylindrical sound-record, 105 a latch mounted on the mandrel and movable in a plane perpendicular to the axis thereof into and out of record-engaging position, record-ejecting means, and a common actuating means for moving the latch out of record-engaging position and subsequently 110 operating said record-ejecting means.

9. The combination in a talking machine of a mandrel for a cylindrical sound-record, 115 a latch at one end of the mandrel for engaging a record thereon to prevent accidental removal therefrom, a manually operable device at one end of the mandrel, mechanism for ejecting the record, a connection between said device and said latch for moving the latch axially out of engagement with the record and then inward out of register therewith, and a connection between said device and said ejecting mechanism for operating the latter.

10. The combination in a talking machine 125 of a mandrel for a cylindrical sound-record, a latch at one end of the mandrel for engaging a record thereon to prevent accidental removal therefrom, a manually operable device at one end of the mandrel mov- 130

able axially and rotatively, mechanism for ejecting the record, a connection between said device and said latch for moving the latch axially out of engagement with the record and then inward out of register therewith as the device is moved first axially and then rotatively, and a connection between said device and said ejecting mechanism for operating the latter as the device is moved 10 rotatively.

11. The combination in a talking machine of a mandrel for a cylindrical sound-record, a shaft for the mandrel, a manually operable knob rotatable on the end of the shaft adjacent one end of the mandrel, a movable latch adapted to engage a record on the mandrel to prevent accidental removal therefrom, and means for moving the latch out of record-engaging position as the knob is turned.

12. The combination in a talking machine of a mandrel for a cylindrical sound-record, a shaft for the mandrel, a manually operable knob rotatable on the end of the shaft adjacent one end of the mandrel, a movable latch adapted to engage a record on the mandrel to prevent accidental removal therefrom, an ejector mechanism operable by the backward rotation of the mandrel, and means 25 for moving the latch out of record-engaging position as the knob is turned and for transmitting the turning motion of the knob to the mandrel to rotate the latter backwardly.

13. The combination in a talking machine of a mandrel for a cylindrical sound-record, a shaft for the mandrel, a manually operable knob rotatable and longitudinally slidable on the end of the shaft adjacent one end of the mandrel, a movable latch adapted to engage a record on the mandrel to prevent accidental removal therefrom, the latch being 40 movable longitudinally with the knob and also movable inward relatively to the knob, and means for moving the latch inward out of record-engaging position as the knob is turned.

14. The combination in a talking machine of a mandrel for a cylindrical sound-record, a shaft for the mandrel, a manually operable knob rotatable and longitudinally slidable on the end of the shaft adjacent one end of the mandrel, a movable latch adapted to engage a record on the mandrel to prevent accidental removal therefrom, the latch being 55 movable longitudinally with the knob and also movable inward relatively to the knob, an ejector mechanism operable by the backward rotation of the mandrel, and means for moving the latch inward out of record-engaging position as the knob is turned and for transmitting the turning motion of the knob to the mandrel to rotate the latter backwardly.

15. The combination in a talking machine of a mandrel for a cylindrical sound-record,

a shaft for the mandrel, a manually operable knob rotatable on the end of the shaft adjacent one end of the mandrel, a movable latch connected with the knob and adapted to engage a record on the mandrel to prevent accidental removal therefrom, and a pin on the mandrel on which said latch is mounted to move inward out of record-engaging position as the knob is turned.

16. The combination in a talking machine of a mandrel for a cylindrical sound-record, a shaft for the mandrel, a manually operable knob rotatable on the end of the shaft adjacent one end of the mandrel, a movable latch connected with the knob and adapted to engage a record on the mandrel to prevent accidental removal therefrom, an ejector mechanism operable by the backward rotation of the mandrel, and a pin on the mandrel on which said latch is mounted to move 75 inward out of record-engaging position as the knob is turned and through which the turning motion of the knob is transmitted to the mandrel to rotate the same backwardly.

17. The combination in a talking machine of a mandrel for a cylindrical sound-record, a shaft for the mandrel, a manually operable knob rotatable and longitudinally slidable on the end of said shaft adjacent one end of the mandrel, a movable latch connected with the knob and adapted to engage a record on the mandrel to prevent accidental removal therefrom, and a pin on the mandrel on which said latch is mounted to move longitudinally with the knob and also inward out 95 of record-engaging position as the knob is turned.

18. The combination in a talking machine of a mandrel for a cylindrical sound-record, a shaft for the mandrel, an ejector mechanism operable by the backward rotation of the mandrel, a manually operable knob rotatable and longitudinally slidable on the end of said shaft adjacent one end of the mandrel, a movable latch connected with the 105 knob and adapted to engage a record on the mandrel to prevent accidental removal therefrom, and a pin on the mandrel on which said latch is mounted to move longitudinally with the knob and also inward out of record-engaging position as the knob is turned and through which the turning motion of the knob is transmitted to the mandrel to rotate the same backwardly.

19. The combination in a talking machine of a mandrel for a cylindrical sound-record, a shaft for the mandrel, a manually operable knob rotatable and longitudinally slidable on the end of the shaft adjacent one end of the mandrel, a movable latch adapted to engage a record on the mandrel to prevent accidental removal therefrom, the latch being 120 movable longitudinally with the knob and also movable inward relatively to the knob, means for moving the latch inward out of record-engaging position as the knob is turned and through which the turning motion of the knob is transmitted to the mandrel to rotate the same backwardly.

record-engaging position as the knob is turned, and means normally urging said knob and latch longitudinally toward the mandrel.

- 5 20. The combination in a talking machine of a mandrel for a cylindrical sound-record, a latch pivoted on the mandrel and adapted to engage a record thereon to prevent accidental removal therefrom, and rotatable 55 means connected with said latch to move the same into and out of record-engaging position.

- 10 21. The combination in a talking machine of a mandrel for a cylindrical sound-record, 15 a pivoted and axially-movable latch mounted on the mandrel and adapted to engage a record thereon to prevent accidental removal therefrom, and rotatable and axially-movable means connected with said latch to 20 move the same into and out of record-engaging position.

22. The combination in a talking machine of a mandrel for a cylindrical sound-record, 25 a pivoted and axially-movable latch mounted on the mandrel and adapted to engage a record thereon to prevent accidental removal therefrom, rotatable and axially-movable means connected with said latch to 30 move the same into and out of record-engaging position, and means normally urging said latch axially toward the mandrel.

23. The combination in a talking machine of a mandrel for a cylindrical sound-record, a shaft for the mandrel, a latch pivoted on 35 the mandrel and adapted to engage a record thereon to prevent accidental removal therefrom, and an arm rotatable on said shaft and connected with said latch to move the same into and out of record-engaging position.

- 40 24. The combination of a mandrel for a cylindrical sound-record, record-engaging means, means for moving said record-engaging means axially of the mandrel to eject 45 the record, means to lock the record on the mandrel, and a common operating means for said record-locking and record-ejecting means.

25. The combination of a mandrel for a

cylindrical sound-record, record-engaging 50 means, cam means operable by the backward rotation of the mandrel for moving said record-engaging means axially of the mandrel to eject the record, means to lock the record on the mandrel, and a common operating 55 means for withdrawing said record-locking means and rotating the mandrel backwardly.

26. The combination of a mandrel for a cylindrical sound-record, a sleeve carrying 60 record-engaging means, cam means operable by the backward rotation of the mandrel for moving said sleeve axially of the mandrel to eject the record, a latch for locking the record on the mandrel, and a common operating 65 means for withdrawing said latch and subsequently rotating the mandrel backwardly.

27. The combination in a talking machine of a mandrel for a cylindrical sound-record, 70 means for ejecting the record from said mandrel operable by the backward rotation of said mandrel, means for locking the record on said mandrel, and a single means for operating said record-locking means and for 75 rotating said mandrel backwardly.

28. The combination in a talking machine of a mandrel for a cylindrical sound-record, means for ejecting the record from said mandrel operable by the backward rotation 80 of said mandrel, means for locking the record on said mandrel, and a single means operable to first release said record-locking means and to thereafter rotate said mandrel 85 backwardly.

29. The combination in a talking machine of a mandrel for a cylindrical sound-record and a latch pivoted on said mandrel and adapted to engage a record thereon to prevent 90 accidental removal therefrom.

30. The combination in a talking machine of a mandrel for a cylindrical sound-record and a latch adapted to engage a record on the mandrel to prevent accidental removal 95 therefrom.

In testimony whereof I have signed this specification.

FRANK C. HINCKLEY.
